Primary Examiner — Natasha Vujcic*Assistant Examiner* — Gilbert B Ford(74) *Attorney, Agent, or Firm* — Dennis D. Brown; Brown Patent Law, P.L.L.C.(57) **CLAIM**

I claim, the ornamental design for a blood pressure transducer holder, as shown and described.

DESCRIPTION

FIG. 1 is a perspective view of a blood pressure transducer holder, showing my new design;

FIG. 2 is a front elevational view thereof.

FIG. 3 is a rear elevational view thereof.

FIG. 4 is a top plan view thereof.

FIG. 5 is a bottom view thereof.

FIG. 6 is an elevational left side view thereof; and,
FIG. 7 is an elevational right side view thereof.

The broken lines in the drawings illustrate portions of a blood pressure transducer holder and form no part of the claimed design.
